UNITED STATES PATENT OFFICE

ARTHUR J. BLAKE, OF BRIDGEPORT, CONNECTICUT, ASSIGNOR TO HARVEY HUBBELL,
INCORPORATED, OF BRIDGEPORT, CONNECTICUT, A CORPORATION OF CONNECTICUT

ATTACHMENT-PLUG CAP

Application filed May 5, 1928. Serial No. 275,327.

This invention relates to attachment plug caps, such as are used on electrical lead wires for portable electrical devices and adapted to be inserted into outlet receptacles for supplying power to these devices from the house wiring system.

It has for an object to simplify the construction and provide a more rigid and reliable mounting for the contacts in the body of the cap.

With the above and other objects in view, the invention consists in certain novel features of construction, combinations and arrangements of parts as will be more fully described, the preferred construction involving my invention being shown in the accompanying drawing. In this drawing,

Fig. 1 is a longitudinal section through a cap embodying my invention taken substantially on line 1—1 of Fig. 2, but with one blade and plate and the free portion of the other plate shown in elevation.

Fig. 2 is an end elevation looking toward the bottom of Fig. 1.

Fig. 3 is a detail section substantially on line 3—3 of Fig. 2.

Fig. 4 is an edge view of the contact blade removed.

Fig. 5 is a front elevation thereof.

Fig. 6 is an end view looking toward the bottom of Fig. 4.

Fig. 7 is a plan view of the binding post plate, and

Fig. 8 is an edge elevation.

At the present time the common construction for attachment plug caps is to form a binding post plate and its knife blade contact in one piece, the blade being bent laterally from one edge of the plate. Each element is mounted in the insulating body by means of an eyelet or insert molded in the body and passing through an opening in the plate with its free end spun over to thus secure the plate to the body. In this arrangement the eyelets or inserts must be very accurately positioned and the operations of assembling the plates on these eyelets and spinning over the eyelets are relatively expensive.

In my present construction I do away with these eyelets and mold the contact blades di-

rectly in the insulating body. The binding post blades are then mounted on these blades so that the blades are not only rigidly and securely mounted in the body, but they also serve as the means for securing the binding post plates to the body.

As shown in the drawing the body 10 is of the usual type molded of suitable insulating material, and is provided with a cavity 11 at its lower side in which the contacts are mounted. It also has a longitudinal opening 12 for the lead wires, not shown, from a portable electrical attachment.

The contact blades 13 are of the usual shape substantially rectangular in cross section and are arranged in parallel relation on opposite sides of the opening 12. Each blade is constructed, as shown more clearly in Figs. 4, 5 and 6. That is, it is provided with an offset 14 spaced from its inner end to provide a shoulder and also to position the inner end portion 15 a suitable distance to one side of the contact portion 13. In mounting these contacts in the body 10 this end portion 15 is molded into the material of the body, and it may be provided with a transverse opening 16 or other suitable means to provide a greater grip and holding effect with the molded material. The opening 16 permits some of the material to flow into it or be forced into it during the molding operation. It is preferred that the contacts be positioned in the body so that the shoulder or offset portion 14 rests against the bottom of a recess in the bottom wall of the recess 11, as shown in Fig. 1. In forming these contact blades a lug 17 is cut on three sides, preferably from the offset portion 14 so that when the portion 15 is bent laterally thereto this lug will extend outwardly from the offset in substantial alignment with the portion 15 as shown in Fig. 4.

The binding post plates 18 are constructed as shown more clearly in Figs. 7 and 8. They are stamped from sheet metal and curved on the outer edges to correspond with the curvature of the recess 11, and carry means for securing the lead wires thereto, such as the binding screws 19. On its inner edge this plate is provided with a notch 20 to receive the body portion of a contact 13, and spaced

laterally from this notch is provided with an opening 21 to receive the securing lug 17. In assembling this plate it is placed in the recess 11 with the contact blade 13 resting in the notch 20 and the lug 17 extending into the opening 21. The blade now rests on the outer wall of the offset 14, and by riveting over the outer free end of the lug 17 the plate 18 is securely fastened to the contact blade 13 and secured by it to the insulating body. It will, of course, be understood that the body is provided with a recess 22 to receive the inner end of the binding screw 19, this recess being molded at the time the body is molded.

15 This arrangement provides a very strong and rigid construction which is firmly mounted in position in the body of the cap, and the contact blade is both directly mounted in the body and acts as a means for securing the binding post plate to this body.

20 Having thus set forth the nature of my invention, what I claim is:

1. In an attachment plug cap, an insulating body member, a blade contact molded at one end in the body, a plate, a lug struck up from the contact extending into the plate and riveted over to secure the plate to the contact, and means for securing a lead wire to said plate.

25 2. In an attachment plug cap, an insulating body member, a blade contact inserted at one end in said body and offset laterally to provide a shoulder, a lug struck from the contact adjacent said shoulder, and a binding 30 post plate resting against said shoulder and provided with an opening through which said lug extends and is riveted over to secure the plate to the contact.

35 3. In an attachment plug cap, an insulating body member, a blade contact molded at one end in said body and provided with a struck-up lug, and a binding post plate having a notch in one edge to receive said contact and an opening for said lug which is riveted over 40 to secure the plate to the contact.

40 4. In an attachment plug cap, an insulating body member, a blade contact inserted at one end in the body and having an offset providing a shoulder, and a binding post plate 45 resting against said shoulder provided with a notch to receive the contact and riveted thereto.

50 5. In an attachment plug cap, an insulating body member, a contact element offset intermediate its ends to provide a shoulder and molded at one end in the body, a plate element resting against said shoulder, a plug struck up from one of said elements and extending through the other element and riveted over 55 to secure the elements together, and means for securing a lead wire to said plate.

60 6. In an attachment plug cap, an insulating body member, a blade contact molded at one end in said body and offset to provide a 65 shoulder resting against the body, a binding

post plate resting against the opposite side of said offset and having a recess in one edge to receive the contact and an opening spaced laterally from said notch, and said blade having a struck-up lug extending into said opening and riveted over to secure the plate to the contact.

70 In testimony whereof I affix my signature.
ARTHUR J. BLAKE.
